DESIGN FOR AN EXTENSION LEAF TABLE

Walter Dorwin Teague, New York, and Walter
Dorwin Teague, Jr., Douglaston, Long Island,
N. Y., assignors to The Enamel Products Co.,
Cleveland, Ohio, a corporation of Ohio

Application October 9, 1940, Serial No. 95,714

Term of patent 7 years

To all whom it may concern:

Be it known that we, Walter Dorwin Teague and Walter Dorwin Teague, Jr., residents, respectively, of New York city, county and State of New York, and Douglaston, Long Island, county of Queens, and State of New York, have invented a new, original, and ornamental Design for an Extension Leaf Table, of which the following is a specification, reference being had to the accompanying drawing, forming a part thereof, wherein:

Fig. 1 is a perspective view of the table with the extension leaves shown in contracted position showing our new design; and

Fig. 2 is a perspective view of the table with the extension leaves shown in extended position.

We claim:

The ornamental design for an extension leaf table, substantially as shown.

WALTER DORWIN TEAGUE.
